UNITED STATES PATENT OFFICE

MAURICE G. KLEMME, OF BELLEVILLE, ILLINOIS, ASSIGNOR TO EAGLE FOUNDRY COMPANY, OF BELLEVILLE, ILLINOIS, A CORPORATION OF ILLINOIS

DESIGN FOR A BROILER TRAY

Application filed February 4, 1933. Serial No. 47,105. Term of patent 3½ years.

To all whom it may concern:

Be it known that I, MAURICE G. KLEMME, a citizen of the United States, and a resident of the city of Belleville, in the county of St. Clair and State of Illinois, have invented a new, original, and ornamental Design for a Broiler Tray, of which the following is a specification.

In the accompanying drawing, which forms part of this specification,

Fig. 1 is a plan view of a broiler tray embodying my invention,

Fig. 2 is a central longitudinal section on the line 2—2 in Fig. 1; and

Fig. 3 is a transverse section on the line 3—3 in Fig. 1.

I claim:

The ornamental design for a broiler tray, as shown.

MAURICE G. KLEMME.
